(57) **CLAIM**

The ornamental design for a felt pad machine needle organizer, substantially as shown and described.

DESCRIPTION

FIG. 1 is a perspective view showing a felt pad machine needle organizer, according to my new design;

FIG. 2 is a front elevational view thereof;

FIG. 3 is a side elevational view thereof, the opposite side being identical thereto;

FIG. 4 is a top plan view, the bottom plan view being identical thereto;

FIG. 5 is a perspective view of a felt pad machine needle organizer showing a second embodiment of my new design;

FIG. 6 is a front elevational view of FIG. 5;

FIG. 7 is a side elevational view of FIG. 5, the opposite side being identical thereto; and,

FIG. 8 is a top plan view of FIG. 5, the bottom plan view being identical thereto.

The needles depicted by means of broken lines in FIGS. 1, 2, 5, and 6 are shown for the purpose of illustrating environmental structure and form no part of the claimed design.
